UNITED STATES PATENT OFFICE.

HERMAN E. BOLDT, OF SHEBOYGAN FALLS, WISCONSIN, ASSIGNOR TO WOOD TIRE
SILO COMPANY, OF SHEBOYGAN FALLS, WISCONSIN, A CORPORATION OF
WISCONSIN.

SILO-HOOP.

1,089,742.

Specification of Letters Patent. Patented Mar. 10, 1914.

Application filed July 17, 1912. Serial No. 709,882.

To all whom it may concern:

Be it known that I, HERMAN E. BOLDT, a citizen of the United States, residing at Sheboygan Falls, county of Sheboygan, and 5 State of Wisconsin, have invented new and useful Improvements in Silo-Hoops, of which the following is a specification.

My invention relates to improvements in silo hoops.

10 The object of my invention is to provide a silo hoop which may not only be more quickly and cheaply made by the process hereinafter described than those heretofore used in the construction of silos, but a hoop 15 which may be made either angular, circular, or angular in part and circular in part, to conform to the space provided therefor, and one which may also be made in a plurality of separate sections, which sections are 20 adapted to be stacked and secured together in a small space for the purpose of shipping and storing, and the separate pieces of the hoop thereafter quickly secured together by unskilled labor, preparatory to being used 25 in the construction of a silo.

My invention is further explained by reference to the accompanying drawings, in which—

Figure 1 represents a plan view of a guide-form used in the manufacture of the hoop sections in which form is shown a plurality of hoop members comprising several short pieces of boards as arranged in the construction of the hoop section. Fig. 2 is a perspective view of the same device shown in Fig. 1, with the hoop members, referred to hereinafter as boards, removed. Fig. 3 is a side view of one end of the form, showing several boards arranged thereon preparatory to being nailed together. Fig. 4 is a perspective view of a plurality of boards forming one end of one of the separable sections of the hoop as the same appears when nailed together. Fig. 5 is a perspective view of the opposite end of a hoop section, which is adapted to be secured to the next adjacent end of the hoop section shown in Fig. 4. Fig. 6 represents a side view of a silo, part broken away, showing 50 the manner of using several complete hoops in the construction of a silo.

Like parts are identified by the same ref-

erence numerals throughout the several views.

The guide-form shown in Figs. 1 to 3 inclusive, comprises the vertical member 1 and the horizontal members 2, which are preferably formed of metal, the parts 1 and 2 being secured together by screws, or in any other convenient manner. It will be 55 understood that the members 1 and 2 may, if desired, be made of wood or other suitable material, and they may be made circular, as shown, or angular, or in part angular and in part circular.

60 3 represents the separate boards, comprising the hoop sections. The boards 3 may be made of a cheap quality of lumber and they are arranged in overlapping series 4, 5, 6 and 7. The number of series of overlapping 65 boards may, however, be increased or diminished, as desired. That the hoop sections may, when completed, have the maximum strength, the meeting ends of the boards 3 of one series, are arranged to 70 break joints with the meeting ends of the next succeeding series. In other words, the central portion of one series of boards is located above the meeting ends of the boards of the next adjacent series. To provide for 75 thus overlapping the boards 3 of the several series a uniform distance, I preferably provide the guide-form with a plurality of stop pins 8, 9, 10 and 11, which are supported from the vertical sides of the member 1 at 80 uniform distances apart, as shown in Figs. 1, 2 and 3. Thus it is obvious that when laying the first series 4 of boards, one end of the first board of the series 4 is placed against the stop pin 8, when the other boards 85 of such series are arranged in a horizontal plane so as to abut against each other as shown in Figs. 3 and 4. When all of the members 3 of one series have been thus laid, the other series 5, 6 and 7 are in like manner laid one above the other, as shown in 90 Figs. 3, 4 and 5.

95 It will be obvious that by the process thus described, the boards of the second and each succeeding series, will overlap the ends of 100 the boards of each preceding series a uniform distance, whereby all the boards of the several series may not only be quickly laid in their proper relative position to each

other, but they may be also retained in such position until they have been nailed or otherwise secured together.

It will also be understood that by the process described, all the boards of a single section are arranged in their proper relative position to each other before being nailed together. When the boards of the several series have been thus arranged together, I preferably use nails of sufficient length to pass entirely through all the boards of such section, whereby the nails driven into the upper series of boards will pass from thence down through the boards of each succeeding series below.

When all the boards of the hoop section have been thus nailed together from one side, a scribing or marking instrument is employed for scribing two circular lines upon the upper series of boards. In thus scribing or marking the hoop sections, a guide bearing of the scribing instrument used for such purpose, is placed against the inner vertical wall of the member 1, while the marking member of such scribing instrument is placed in contact with the upper surface of the hoop section, whereby the marking instrument is caused to describe a circle concentric with the circle of the vertical member 1, as indicated by the dotted line 12. When one circular line has been thus scribed near the outer edge of the hoop section, such scribing instrument is adjusted to form a line concentric therewith at the inner edge of such section, as indicated by the dotted line 13. When the boards have been thus nailed together and scribed upon one side, the hoop section thus made is removed from the guide form and inverted, when they are all again nailed together from the opposite side of such hoop section. When the hoop sections have been thus nailed from both sides and marked, they are placed upon a saw when they are cut to conform to the circle described by said dotted lines 12 and 13, whereby the surplus material 14 and 15 upon the exterior and interior sides of said scribed marks 12 and 13 are removed, when the hoop sections, the ends of which are shown in Figs. 3 and 4, are thereby complete and ready for storage, shipment or use.

While I have shown and thus far described the hoop sections of circular form, it will be obvious that with slight modifications, such sections may be made angular, or in part angular and in part circular, as above stated, and that when such modified forms of hoop sections are thus made, the shape of the guide-form must be changed accordingly. It will also be understood that the hoop sections may be made to form a quarter, half, third or any other segment of a circle or portion of a hoop used in the construction of a silo. When, however, the hoop sections

are made for silos of large dimensions, such hoops may be subdivided to form a quarter or even a less portion of a circle, and that when the hoops are made for smaller silos, such sections may be made to describe a third or half circle. The length of the hoop sections in this respect may, however, be varied to meet the requirements or convenience of the manufacturer.

It will now be understood that the hoop sections thus formed may be secured together in a compact or convenient form for storing or shipping and that when desirous to use the same in the construction of a silo, the several hoops are supported one above the other in a vertical series from the foundation to the top of the silo, substantially as shown in Fig. 6. When thus supported, the interior wall 16 may be readily nailed to the inner surface of the several hoops, and the exterior wall 17 nailed to the exterior surface of such hoops, when the hoops serve to retain the walls 16 and 17 at the desired uniform distance apart, whereby a narrow space 18 is formed between said walls. For convenience in construction, the several hoops are supported one upon another at the required distances apart by the vertical standards 19, an annular series of said standards being interposed at slight distances apart between the opposing surfaces of said hoops, whereby each succeeding hoop above the first may be supported from the hoop below, and the several hoops used in the construction of a silo thus retained at the required distance apart before the vertical walls 16 and 17 are secured thereto. The vertical walls 16 and 17 are preferably formed of matched flooring or other suitable lumber which is secured together and to said hoops in the ordinary manner.

Having thus described my invention, what I claim as new, and desire to secure by Letters Patent, is—

1. As an article of manufacture a sectional or knock-down silo hoop, comprising separate hoop sections, each formed of several layers, each layer made up of several boards, the boards of one layer being arranged to break joints with the boards of the other layers, both throughout the body and at the ends of the several sections, so that, when the several sections are assembled in a hoop, the ends of the layers of one section break joints with those of the abutting section, and the sections may be secured together to form a hoop by nailing through the overlapping ends of the several sections.

2. As an article of manufacture a sectional or knock-down silo hoop, comprising separate hoop sections, each formed of several layers, each layer made up of short boards, the boards of each layer breaking joints with the boards of other layers, the layers being

nailed to each other and the several layers extending one beyond another at the ends of each section, and in reverse order at opposite ends of the section, so that, when the several sections are assembled in a hoop the ends of the layers of one section overlap and break joints with those of the abutting section, and the sections may be secured to

gether by nailing through such ends to make a complete hoop.

In testimony whereof I affix my signature in the presence of two witnesses.

HERMAN E. BOLDT.
